GRILLEWORK FOR TREILLAGES, ROOM DIVIDERS OR THE LIKE

Robert F. Seery, Oak Brook, Ill., assignor to Julius Blum & Co., Inc., Carlstadt, N.J.

Filed Jan. 3, 1972, Ser. No. 215,267

Term of patent 14 years

Int. Cl. D25—02

U.S. Cl. D54—2 T

FIG. 1

FIG. 2

FIG. 3

FIG. 4

FIG. 5

FIG. 6

FIG. 7

FIG. 1 is a top plan view of a grillework for trellages, room dividers or the like.

FIG. 2 is an elevational view of the grillework,

FIG. 3 is a side elevational view thereof,

FIG. 4 is an enlarged transverse sectional view taken along line 4-4 of FIG. 2,

FIG. 5 is an enlarged transverse sectional view taken along line 5-5 of FIG. 2,

FIG. 6 is an enlarged transverse sectional view taken along line 6-6 of FIG. 2, and

FIG. 7 is an enlarged transverse sectional view taken along line 7-7 of FIG. 2.

I claim:

The ornamental design for a grillework for trellages, room dividers or the like, as shown and described.
